UNITED STATES PATENT OFFICE.

ROBERT G. BROWN AND JOHN E. STRAUETELMEIER, OF ELYRIA, OHIO.

Sheet-Metal Replayer.

1,230,732.

Specification of Letters Patent.

Patented Nov. 4, 1910.

Application filed September 15, 1910. Serial No. 120,302.

To all whom it may concern:

Be it known that we, ROBERT G. BROWN and JOHN E. STRAUETELMEIER, both citizens of the United States, and residing at Elyria, in the county of Lorain and State of Ohio, have invented a new and Improved Sheet-Metal Replayer, of which the following specification is a full disclosure.

This invention relates to phonograph repeaters and it seeks to develop a replaying mechanism (1) embodying elements so devised as to be constructible at a minimum cost, as by die-press operations; (2) so compact and low that it may be placed adjoining an ordinary turn-table without interference with the protruding rims of extra-large records; (3) made up mainly of sheet-metal stampings inter-fitted and combined to enable single elements or single groups of elements to exercise more than single functions, thereby decreasing the number of parts; and (4) to achieve in a notably effective manner the various objects of the invention broadly revealed and claimed in the U. S. patent of R. G. Brown, No. 1,221,002 issued March 27, 1911, by very simply embodying the more essential characteristics thereof in a manner improving upon and simplifying the construction of our U. S. Patent 1,234,621 issued July 24, 1917.

Another object is to devise an appliance particularly adapted for "mail order" sales, and which will be free from elements not ordinarily understood, such as electrical appliances and which will, in lieu thereof, embody very simple mechanical parts such as mechanical trip devices in place of electrical contact systems which, though perhaps better, may prove more troublesome.

Another object is to devise an attachment which can be used in conjunction with phonographs having a tone-arm pivoted by means of a universal joint to the frame of the machine, and which will be sufficiently low to lie under the overhanging rim of a large sized record.

Other objects will be in part obvious from the annexed drawings and in part indicated in connection therewith by the following analysis of this invention.

This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same by numerous modifications in structure and relation contemplated by this invention, drawings depicting a preferred form have been annexed, as a part of this disclosure, and in such drawings, like characters of reference, denote corresponding parts through all the views of which:

Figure 1 is a plan of a conventional phonograph having this fixture combined therewith showing the positions of the axis when the stylus has been raised one-half of its full uprise and the parts have been re-latched but not withdrawn. Fig. 2 is a side elevation showing how the lowness of this attachment enables an extra-large record to overhang it without interference. Fig. 3 is a sectional plan of the device on the line 3-3 of Fig. 4 with the elements in their non-tripped or dormant positions; Fig. 4 is a longitudinal sectional view on the line 4-4 of Fig. 3. Fig. 5 is a view similar to Fig. 3 showing the parts immediately after being tripped and before being re-latched. Fig. 6 is a cross section on the line 6-6 of Fig. 3. Fig. 7 is a cross sectional view on the line 7-7 of Fig. 3. Fig. 8 is an inverted perspective of the stamped-up main-frame. Figs. 9 and 10 are perspectives of the top and the bottom portions of the sub-frame. Fig. 11 is a perspective of the latch. Fig. 12 is a perspective of the brake-element. Fig. 13 is a perspective of the dual-fulcrumed tripping, relatching and restoring lever. Fig. 14 is a perspective of the link for vibrating the stylus-lifter. Fig. 15 is a perspective view of the member forming a guide for the brake-element and a bearing for other movable parts.

One of the pronounced characteristics of this improvement resides in the unique utilization of sheet-metal in such a manner that the elements are all, or in the main, thin in the horizontal planes, i. e., they are arranged horizontally flatwise so as not to be very high in the aggregate even when they are superimposed. The base or frame is designed to be made from a single sheet-metal stamping formed in the shape of a box with the portions bent in several ways. Thus, the base 15 provides two opposite tongues, D and E, providing slots α and β which are elongated in a direction away from the turn-table to aid in ultimately accurately locat-

2

ing the attachment. Thus, it is first pressed against the edge of the turntable, the screws are inserted in the far ends of the slots, and, before they are tightened down finally, the 5 device is then pulled as far away from the turn-table as the length of the slots will permit; and then when the screws are tightened down, the device will be accurately located. The base also provides an ear 9' which is 10 bent inward and has a hole registering with a hole in the part of said base 15 forming a cover, and said holes are adapted to receive a hollow tube or post 9 which supports the davit 11. The tongue or extension E 15 has an upstanding ear P having an arc-slot o to receive the clamping screw of a stop element M used to determine the initial starting point of the tone-arm. A part termed the guide member shown in Fig. 15 is set 20 cured to the side of the base-frame by screws 20^a and has two ears 20 extending therefrom which serve to position and act as a bearing for a shaft which is the axis of swing of the sub-frame used for shifting the power off 25 and on. An upward extension 21 of this guide member and the opening 22 in the end of the base-frame act as guides and bearings for the shiftable brake element shown in Fig. 12.

30 In general, this invention contemplates a low, compact self-contained device adapted to enter into combination with the conventional elements of a standard phonograph to function as above-named, and specifically it 35 embraces all or many coördinated sub-combinations including (A) a sound-box lifter, which at appropriate intervals lifts and lowers the stylus; (B) a tone-arm shifter which carries the stylus from the end to the 40 beginning of the record; (C) a motion-transmission which furnishes the necessary gears and shifts resulting in an actuation of the lifter and shifter; (D) a power connector which is in the nature of a clutch-mechanism and which at appropriate intervals 45 connects the transmission with the primary source of power, which may preferably be the turn-table itself but which may be any easily accessible motor-driven element; (E) 50 a trip-system which is effective automatically to throw the power connector into action at the appropriate station in the record; (F) a control-lever which automatically effects a disconnection of the power-connector and normalizes the relation of the trip 55 to the mechanism; (G) an adjuster which predetermines the number of times the mechanism operates to replay the record; and (H) a brake which is conveniently 60 caused to operate to conclude the performance.

The sound-box lifter and tone-arm shifter in this embodiment is compacted and condensed into a single sub-mechanism embodying a tone-arm 4 to which is pivotally

mounted a reproducer carrying a stylus 3; the whole being to all intents and purposes a single unit providing for a horizontal swing at the vertical central axis 4^a and also a vertical about the horizontal axis 4^b. This 70 provides all means necessary for a normal playing of the stylus as well as lifting, returning and lowering it. It may be explained that when the stylus-holder 4 is lifted to raise the stylus, it must not begin 75 the swing back until the stylus has entirely cleared the record, otherwise it would be scratched. The lifting and shifting means embodies a davit 11 which has its lower end journaled in a hollow post 9 projecting 80 from the base-frame 15 and the upper end of this davit is in the form of an arm 11^c having an eye 11^a at its extremity to which is attached the cord 12. This arm extends through a hole in the upper end of the post 9 85 and a screw 11^b serves to lock it in any desired position. This hole is sufficiently high to locate the arm 11^c above the tone-arm so that a pull on the cord 12 will lift the tone-arm about its horizontal axis 4^b thus elevating 90 the stylus.

This invention contemplates a means that will come effectively into action only after the stylus has been raised and in this particular embodiment great simplicity has been 95 attained by intimately incorporating this means with the stylus-lifter, and this has been done by a peculiar relation between the axes 11^b and 4^a of the davit and tone-arm, respectively, and the arc of swing of the 100 point 11^a. That is to say, in its normal or stylus-lowering position, the davit 11 is in a position, such as shown by Fig. 1, that the straight line from the point 11^a to the point 12^a is not sufficiently off a "dead center" 105 relation with the axis 4^a to cause the tone-arm to swing, but when the davit 11 swings into its uplifting position, this straight line becomes in a pronounced off-set relation with the axis 4^a with the result that a pull 110 on the cord 12 not only tends to lift the stylus but also imposes a sufficient turning movement of the tone-arm to urge it gently, yet sufficiently, toward its initial position. It will be observed that the relation of the 115 point 11^a to the two axes 4^a and 11^b is such that when the arm 16 rotates in one direction about its own axis, the tone-arm 4 will swing in the opposite direction about its own axis, and this peculiar relation of parts carries 120 the advantage that a single means is enabled to perform the two-fold function of lifting and shifting the stylus in a manner so graduated as not to scratch the record.

The motion transmission is the mechanism 125 or train of elements that results in the actuation of the stylus-replacing means by power derived from some motor driven part, such as the turn-table 1; and which preferably embodies reduction gears so that the alti- 130

mate motion will be slow and deliberate and the stylus will be handled gently and without jerks and thus save the record from scratches. In this embodiment, this transmission is in part stationary and in part is bodily shiftable for power connecting purposes. The stationary part comprises a shaft 19 pivoted at its lower end in the ears 20 of guide member M. The upper end of this shaft 19 is provided with an eccentric pin 19^a which is connected with the end of the arm 16 by means of the link 17 whereby the davit 11 may be rocked slowly. This shaft 19 derives motion from the clutch element or wheel 29 through a train of reduction gears 24, 25, 26 and 27, the shafts of which are all pivoted to the side plates 23 of a rocking-frame. This rocking-frame is in the nature of a sub-frame composed of sheet-metal stampings. Thus, the upper plate, as shown best by Fig. 9, has recesses a and b which receive tongues provided by the upstanding portions f and g of the lower plate. Suitable posts bind these plates together. Both gear-sets 24-25, 26-27 have a pronounced reduction effect with the consequence that the crank pin 19^a is but very slowly turned, although the friction wheel 29 may rotate several times during each revolution of the turn-table.

The power connector is an arrangement in the nature of a clutch and it enables the turn-table to operate during the normal playing of a record without any concomitant operation of the return mechanism. Preferably this means is located so as to disconnect as many parts as possible from the source of motion, to avoid needless wear or noise, and preferably the wheel 29 is therefore entirely withdrawn from the turn-table. This is conveniently done by pivoting the plates 23 of the sub-frame to the shaft 19 so that the shaft 28 of the friction wheel will be carried by the remote free-swinging portion of the sub-frame. The position of this sub-frame is in turn determined by the following arrangement:-

The lever control for the swinging power connector function first to unlatch and resiliently swing the sub-frame to bring the friction wheel 29 into engagement with the periphery of the turn-table and to maintain this engagement until the tone-arm has been shifted to its initial point, and in the meanwhile to effect a relatching of the control-lever, and then through the same lever to withdraw the friction-wheel and permit the record to be played without interference. This triple action is very easily effected by the multiple-fulcrum lever-system comprising a sheet-metal lever 31 which is permanently pivoted at 30 to the plate 23 of the swinging sub-frame and which (in the position of the parts shown by Fig. 3) can through the pull 35 of the spring 38 (when unlatched) be turned

about the stationary fulcrum point 19 by acting through the flat edge 18 of the cam-plate 18. When this movement takes place under these circumstances, the lever 31 and the sub-frame 23 act as a unit and swing as a unit about the pivot 19, since the lever 31 does not turn on the pivot 30 which attaches it to the sub-frame. That is to say, the hook-like end of the lever 31 has entered a right-angle notch 32 in the cam-plate 18 so that it may rest against the edge 18^a thereof which, in a sense, constitutes a stationary fulcrum enabling the lever 31 at the point 30 to pry the plate 23 around the axis 19. Normally, the spring 38 is precluded from swinging the lever 31 by means of a pin or detent 33 which engages with the notch 34 of a latch 35 pivoted at 36 to a frame-element and spring-pressed into its obstructing position by the pull of the spring 38 at the end 80 of the arm 31. The effect of the aforesaid movement is to bring the wheel 29 against the rotating turntable and cause the wheel to turn. The rotation of the cam 18 begins the moment the wheel 29 starts to actuate 90 the davit 11 and this rotation is anti-clockwise and moves the cam 18 so as to bring the raised portion 18^c underneath the end of the lever 31 so as to force said end away from the shaft 19 into the position shown by 95 Fig. 5 and swing the lever about the pivot 30 (the sub-frame remaining still) until the latch-pin 33 has passed the notch 34 in the latch 35. This movement takes place against the resistance of the spring 38. This condition remains unchanged while the periphery of the cam-plate 18 rides against the end of the lever 31 and until the point 18^a passes the end of the lever 31, whereupon the fulcrum provided by the cam 18 will have disappeared. The cam has now ceased to oppose the spring which thereupon immediately moves the pin 33 against the stationary fulcrum provided by the notch 34 of the latch 35, so that the spring now tends to turn 110 the lever 31 around the pin 33 as a fulcrum and this acts to throw the pivotal connection 30 in the opposite direction and, of course, causes the sub-frame to swing back about the pivot 19 into the position shown by 115 Fig. 3, thereby withdrawing the friction wheel 29 so that all motion ceases in the entire attachment. The sub-frame continues to withdraw until the end of the lever abuts the part 18^a again, when the position of Fig. 120 3 is attained. This action has resulted in an elevation of the stylus, a swinging of the tone-arm, and a replacement of the stylus. Now, the stylus is in a position to replay the record and will continue to do so until 125 a trip-system comes into effect to release the latch 35 and cause the attachment to refunction in restoring the stylus to its initial position.

The trip system is entirely mechanical in. 130

2
this embodiment and it proposes an element such as the arm H pivoted about the pin I and having a contact surface h adapted to bear up against the arm 37 extending from the latch 35 so as to swing the latch to release the pin 33, which is stamped up from the lever 31. This arm H is frictionally clutched to a trip lever J which is extended to locate its free end in a position to be abutted and moved by the sound-box and consequently cause the arm H to operate the latch. As shown by Fig. 6, a spring-washer L is seated in a circumferential slot near the end of the post I and compresses the arm J between the friction disk W and shoulder Y of the pin I with just sufficient force to permit of an easy adjustment of the trip-arm J by the hand and yet to transmit without slipping enough pressure to throw the latch. K represents a shoulder integral with the pin I for fixing it on the frame. The arm H is rigidly secured to the pin I between the riveted or turned-over portion of said pin and shoulder Y. In this way the latch may be caused to operate at any predetermined limiting of the stroke of the tone-arm 4, with the result that the tone-arm is uplifted and permitted to swing in an anti-clockwise direction. This movement is in turn limited by a stop consisting of a part M which can be clamped in any angular adjustment to the upstanding part P by the thumb screw O.

The adjuster operates to determine the number of times the record will automatically replay, and it comprises an escapement-like device which, after a predetermined number of countings, is released to set a brake against the turn-table. In this embodiment, the parts are composed mainly of sheet-metal and the whole sub-combination is subject to displacement as a unit. Thus, a brake proper consists of a flat strip T, with both ends bent at about right angles 45 slidably supported in the opening 22 of the frame and guided by the bent up portion 21 of the guide member N which runs in a cut-out part of the rear downward extension of the brake, and having its forward end 50 protruding and turned down so as to act as a braking surface 42 against the periphery of the turn-table. As shown by Fig. 12, the blank is stepped-up slightly at its other end and is laterally extended and carries a post 55 riveted thereto. This post pivotally carries a hand-adjustable ratchet 43 having a number of ratchet-teeth 6 that, by an intermittent engagement with the upturned lip 45 of link 17, operate to turn the ratchet-wheel one notch for each stylus lifting cycle. The ratchet-wheel is also provided with a release in the nature of a cut-away portion or slot R. A pin S normally bears against the periphery of the ratchet-wheel and prevents the spring 46 from bodily shifting this

sub-mechanism into its braking position; but when this slot R coincides with the pin S, a release is effected and the brake T acts effectively.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should and are intended to be comprehended within the meaning and range of equivalency of the following claims.

It will be seen, therefore, that the mechanism will repeatedly go through its cycle of replaying a record unless the brake functions; but the brake cannot be thrown in until the ratchet-wheel has been moved (either manually or by the reciprocating lip 45) until the slot R coincides with the pin S. The lip 45 can move the ratchet-wheel only by periodically acting against the shoulders successively presented by the ratchet-teeth 6. If the blank-region of the ratchet-wheel be located in the path of the lip 45, it is ineffective and the device will continue to replay the record indefinitely. If the parts be in the position shown by Fig. 5, the stylus is engaged with the record when the lip 45 is retracted; and the record will be played once and will then trip the parts so as to cause the wheel 29 to again advance the lip 45, and it will engage the shoulder of the single tooth remaining and advance the ratchet-wheel until the pin S registers with the slot R, as shown by Fig. 3, and permits the brake to set and stop the phonograph. If the ratchet-wheel be set so that six shoulders can be acted upon by the lip 45, the machine will repeat six times. It is noted that eight shoulders are provided for (one of them being the edge of the slot R), so that eight replays can be had if desired.

Having thus revealed this invention, we claim as new and desire to secure the following combinations of steps and elements, or equivalents thereof by Letters Patent of the United States:

1. A unitary self-contained attachment for a conventional phonograph combining means for raising, shifting and lowering the stylus to its starting station; mechanism driven by a motor-driven part of the phonograph for actuating said means repeatedly to automatically replay the selection; a mechanical trip actuated in consequence of the movement of the stylus; a hand-adjustable ratchet wheel; means cooperating therewith for causing said mechanism to function only the predetermined number of times, said means comprising a reciprocating detent.

2. A phonograph re-player combining an automatic returning mechanism; a part reciprocated thereby; a brake-element normally urged into its arresting position; 5 means adapted to restrain said brake and a rotatable segment having teeth intermittently fed by said reciprocating part and constructed to be released when it attains a predetermined position to permit the operation of said brake.
3. A re-player combining a bodily-shiftable element; a notched disk pivoted thereto; a spring tending to shift said element; a

part abutting said disk to restrain its displacement; and reciprocating means for 15 turning said disk step-by-step into a position free from said part.

In witness whereof we hereunto subscribe our names, as attested by the two subscribing witnesses.

ROBERT G. BROWN.
JOHN E. STRIETELMEIER.
